UNWINDING HEAD FOR BOLTS OF FABRIC

Nathan Obedin, Brooklyn, N. Y.

Application September 14, 1944, Serial No. 554,069

3 Claims. (Cl. 242—73)

This invention relates to improvements in devices for unwinding bolts of cloth, and an object of this invention resides in the provision of a mounting for rotatably supporting a bolt of cloth upon a frame for conveniently unwinding lengths of cloth from the bolt prior to laying out the cloth for cutting.

Another object of this invention is to provide a shaft having blade members adjustable lengthwise of the shaft and arranged in pre-aligned relation for embedding the blade members in the end portions of a bolt of cloth to accommodate bolts of different lengths.

Another object of this invention is to provide two slidable blade members for engaging the opposite ends of a bolt of cloth for supporting the bolt, and comprising bifurcated blade members spaced apart from each other on the shaft and seating in keyways on diametrically opposite sides of the shaft and being insertable in the bolt between the core board and the cloth.

Another object of this invention resides in the employment of flat triangular blade members made of sheet metal, each blade member being centrally slotted so as to form a bifurcation and the metal at the bifurcated portion being seated in diametrically opposite keyways in the shaft, whereby the edges of the blade members at the slot are covered and concealed and including the apex portion of the blade member, the respective blade members being insertable in a bolt of fabric without danger of tearing or injuring delicate fabric.

With the above and other objects in view, the invention will be hereinafter more particularly described, and the combination and arrangement of parts will be shown in the accompanying drawing and pointed out in the claims which form part of this specification.

Reference will now be had to the drawing, wherein like numerals of reference designate corresponding parts throughout the several views, in which:

Figure 1 is a front elevation of my fabric bolt mounting and supporting head rotatably supported in bearings in an upright frame.

Figure 2 is a top view of the mounting and supporting head.

Figure 3 is a plan view of one of the blade members.

Figure 4 is a cross-sectional view of the shaft on an enlarged scale, showing the diametrically positioned keyways, the section being taken as on line 4—4 in Figure 2.

Figure 5 is a cross-sectional view of the head,

on an enlarged scale, the section being taken as on line 5—5 in Figure 2.

In the illustrated embodiment of the invention the numeral 10 indicates a rotatable supporting and mounting head for bolts of fabric. The head 10 comprises an elongated shaft 11 having blade members 12 slidably mounted thereon. The shaft 11 is designed for mounting in a U-shaped frame 13 or in similarly shaped cloth winding machines. The frame 13 has upright arms 14 secured to a base 15. The upper ends of the arm 14 have bearings 16 having open top faces whereby the shaft 11 may be placed vertically in the bearings and rotatably supported. The shaft 11 has a circumferentially grooved portion 17 at one end, providing a shaft portion of smaller diameter adapted to rest in one of the bearings 16. The side edges defining the grooved portion 17 provide abutments on each side of the bearing which retain the shaft against movement in an axial direction.

As best shown in Figures 2 and 4, the shaft 11 has keyways 18 which are diametrically positioned. The keyways are spaced apart leaving the middle portion of the shaft solid and peripherally intact. The strength of the shaft 11 is thus maintained at the location of maximum deflection. The keyways 18 are axially aligned and maintain the blade members 12 in axial alignment.

Each blade member 12 has an apertured collar 20 for the shaft 11. The collar 20 has a screw 21 threaded therein, the screw serving for adjustably securing the blade member on the shaft. Integral with the collar 20 is an elongated cross-bar 22.

The bar 22 is positioned in offset relation from the aperture in the collar so as to clear the shaft 11 passing therethrough. Secured to the bar 22 by screws 23 is a sheet metal plate 24.

The plate 24 has an offset portion 25 extending in the direction of the shaft 11 and terminating in a flat portion 26 in a plane parallel with the axis of the shaft. The flat portion 26 extends in a direction away from the collar 20 and is angularly directed toward the axis of the shaft. The flat plate portion 26 is centrally slotted at 27 to form a bifurcation and two arms 28.

The side edge portions of the arms 28 at the slot 27 are designed to seat in the keyways 18 whereby the blade member 12 is slidable lengthwise of the shaft.

It is to be noted that the side edges of the arms 28 at the bifurcation 27 are covered and concealed by the shaft 11 and including the pointed free end portions 29 of the arms.

The core 30 of the bolt of fabric 31 is usually constructed of frail cardboard. The shaft 11, being longer than the bolt of fabric, provides a reinforcement by which the bolt of fabric may be safely rotatably supported.

In the operation of the invention, one of the blade members 12 is removed from the shaft to allow the shaft to be inserted into a bolt of fabric. The bolt is then moved up to and against the offset portion 25 of the blade member. The other blade member is then mounted on the shaft and inserted with the free end portions 29 of the arms 28 entering the opposite end of the bolt until the distance between the opposite offset portions 25 equals the width of the bolt. The screw in the collar 20 of the last mentioned blade member is turned against the shaft to hold the blade member in this engaged position.

The concealed free end portions of the blade members are insertable between the fabric layers and the core without any danger of tearing or damaging the fabric.

It is to be noted that the blade members 12 are held to the shaft 11 by the keyways and that the free end portions 29 of the arms 28 are rigidly held and prevented from swaying.

The unwinding head herein disclosed is adapted for use in cloth measuring machines, cloth spreading machines and the like. For the purpose of this disclosure the unwinding head is shown mounted in an upright frame having a base on which the unwound cloth may be spread.

In accordance with the patent statutes I have described and illustrated the preferred embodiment of my invention, but it will be understood that various changes and modifications can be made therein without departing from the spirit of the invention as defined by the appended claims.

I claim:

1. A supporting and mounting head for unwinding a bolt of fabric having a rectangular core at its central portion, comprising an elongated shaft having two diametrically positioned keyways at each end, two centrally slotted triangular blade members having bifurcated arms, the side edge portions of said arms at said slot being seated in said keyways and adapting said blade members for slidable movement relative to said shaft, said arms being integral with a cross-bar, said cross-bar being positioned in offset relation from said arms and being clear of said shaft, said cross-bar providing an abutment for said bolt of fabric, means for detachably secur-

ing said blade member on said shaft, said keyways being in longitudinal alinement and causing said blade members to be in alinement while at opposite ends of said shaft and in alinement with said core, the edges of said blade members at said bifurcation being covered and concealed by said shaft and including the apex portion of said blade member.

2. In a rotary supporting and mounting head for a bolt of fabric having a core at its central portion, an elongated shaft having two elongated keyways at each end, said keyways being on diametrically opposite sides of said shaft, two centrally slotted blade members having bifurcated arms, the side edge portions of said arms at said slot being seated in said keyways and adapting said blade members for slidable movement lengthwise of said shaft, said arms being integral with a cross-bar, said cross-bar being positioned in offset relation from said arms and being clear of said shaft, said cross-bar providing an abutment for said bolt of fabric, means for detachably securing said blade members on said shaft, said keyways being in longitudinal alinement and causing said blade members to be in alinement while at opposite ends of said shaft and in alinement with said core, the side edges of said blade members at said bifurcation being covered and concealed by said shaft and including the pointed free end portions of said arms.

3. In a rotary supporting and mounting head for a bolt of fabric an elongated shaft having two elongated keyways at each end, said keyways being on diametrically opposite sides of said shaft, two centrally slotted blade members having bifurcated arms, the side edge portions of said arms at said slot being seated in said keyways and adapting said blade members for slidable movement lengthwise of said shaft, said arms being integral with a cross-bar, said cross-bar being positioned in offset relation from said arms and being clear of said shaft, said cross-bar providing an abutment for said bolt of fabric, means for detachably securing said blade members on said shaft, said keyways being in longitudinal alinement and causing said blade members to be in alinement while at opposite ends of said shaft, the side edges of said blade members at said bifurcation being covered and concealed by said shaft and including the pointed free end portions of said arms, said free end portions being rigidly held and prevented from swaying.

NATHAN OBEDIN.
